INVENTOR
Max Menkin

BY C.P. Goepel.

ATTORNEY

UNITED STATES PATENT OFFICE.

MAX MENKIN, OF NEW YORK, N. Y.

POWDER PUFF.

Application filed December 27, 1920. Serial No. 433,194.

To all whom it may concern:

Be it known that I, MAX MENKIN, a citizen of Russia, and resident of New York, county of New York, State of New York, 5 have invented certain new and useful Improvements in Powder Puffs, of which the following is a specification.

This invention relates to improvements in powder puffs and has for its general object the provision of a powder puff by means of which powder may be evenly applied without smearing or streaking, a powder puff so constructed that it may be made by machine and have, both in point 10 of appearance and in function, all of the other advantages heretofore had only with hand made powder puffs.

To this end the invention resides in a machine made powder puff, the back or 20 stock of which is formed of textile material and gathered or plaited and made flexible so as to correspond with an ordinary hand made powder puff and as distinguished from machine made powder puffs, which as 25 heretofore constructed have been provided with rigid or unyielding backs or stocks and without pleats.

Other objects will appear and be better understood from that embodiment of the invention of which the following is a specification, reference being had to the accompanying drawings forming part thereof, and in which:

Figure 1 is a perspective of the invention; 35 Figure 2 is a detailed perspective of the components of the frame;

Figure 3 is a detail of the plies forming the stock;

Figure 4 is a detail side elevation partly 40 in section of the stock.

Figure 5 is a detail partly in section of the interior of the pad;

Figure 6 is an enlarged cross sectional 45 view of the powder puff; and

Figure 7 is a detail perspective of the clamping ring and showing the means for securing the handle.

The pad *a* of the powder puff may be of 50 any preferred size and shape and when made circular, as shown, consists of a circular shaped body *5*, formed of soft fluffy material, as for instance lamb's wool, swan's down, velour and the like. The marginal portion of body *5* embraces an annulus *6*,

which operates to reenforce the pad, and is 55 formed of suitable rigid material, as metal, and provided with an inwardly extending flange *7*, which functions to provide a generous bearing surface and marginal reenforcement for the flat face of the body *5*. 60 The flange *8* disposed at right angles to flange *7* operates to reenforce the side of the pad and the relative sizes of the pad *5* and annulus *6* are such as will permit of bending the marginal portion around the 65 edge of flange *8* and into the space surrounded thereby.

The body of the stock *b* consists of superimposed layers of preferably textile material of any fanciful contour, shade or design. 70 The outer layer *9* conforms in contour to the pad *a* and is connected at its central portion to the inner layer *10* by an eyelet *13*. The eyelet *13* operates to secure the converging edges of the pleats or folds *14* 75 of the outer layer *9* against displacement. An annulus *11* corresponding in cross section to the annulus *6* is provided for the back or stock *b* and the marginal portion of the outer layer *9* is such that it may be 80 bent around the edge of the annulus.

The inner layer *10* conforms approximately to the area of the annulus *11* and is adapted to be secured therein by a clamping ring *12*, which is of a size to snugly 85 fit within the annulus and thereby operate to render the inner layer *10* taut or tensioned. The area of the outer layer *9* is such that its marginal portion is extendible over the edge of the annulus *11*, as shown 90 in Figure 6, and when the parts are disposed as shown in the last named figure the area of the back or stock *b* is such that it may be readily assembled with the pad *a* by telescoping therewith. That face of the ring 95 *12* which is outermost when the stock is assembled, as shown in Figure 4, is provided with upstruck prongs *16* which operate to engage the free ends of the doubled length of flexible materials, such as ribbon, constituting the handle *15* and thereby hold 100 the said handle against displacement. It will be noted by referring to Figure 4 that the intermediate portion of the handle *15* extends through the eyelet *13* so as to provide a loop forming a convenient finger hold 105 in using.

The back or stock is assembled with suit-

able machinery adapted for fastening the eyelet 13 to the layers 9 and 10 and gathering the outer fold and turning the marginal portion thereof around the annulus 11 and 5 also for positioning the clamping ring 12 in the annulus 11. Suitable machinery is then employed for bending the marginal portion of the body 5 of the pad around the annulus 6 and for rolling the flange 8 10 of the annulus 6 on the side of the backing or stock after the parts have been assembled as shown in Figure 6. In assembling the stock *b* with the pad *a* the upstruck prongs 16 will bend or clinch on 15 the flange 7 of annulus 6 and thereby operate more effectively to hold the handle 15 against displacement.

The presence of the space between the stock *b* and pad *a* and the resiliency of the 20 stock due to the tension thereof operates to admit of a relative yielding between the stock and pad in applying powder for instance to the face by tapping the same gently with the pad. The application of a substantially even coat of powder to the face 25 results from the relative yielding of the stock and pad as distinguished from an uneven application or smearing which is had with puffs heretofore constructed with machinery and having rigid and nonyielding stocks.

Although I have shown and described an ideal form of my invention it is to be understood that I am not to be limited to the 35 form of invention herein described, it being obvious that minor changes may be made within the scope claimed without departing from the spirit or sacrificing any of the advantages of the invention.

40 I claim:

1. A powder puff comprising a pad section, and a stock section, said stock section 45 consisting of an annulus, a piece of fabric stretched thereover, a second piece of fabric stretched under the first mentioned strip of fabric, a clamping ring fitted within the annulus and having portions struck therefrom, a ribbon engaged with the struck portions of the clamping ring, said struck portions of 50 the clamping ring adapted to engage with parts of the pad when the sections are assembled.

2. A powder puff comprising interfitting stock and pad portions, the pad portion 55 consisting of an annulus and a substantially circular-shaped piece of fabric the marginal portion of which is bent over an edge of the annulus and clamped by the stock portion, the stock portion consisting of an annulus and a piece of fabric having its marginal portion bent over an edge of the annulus, and clamping means disposed in the second 60 named annulus and superimposed on the marginal portions of said second named piece of fabric and operating to tension the same.

3. A powder puff comprising interfitting stock and pad portions, the latter of which consists of an internally flanged annulus and a substantially circular shaped piece of fabric the marginal portion of which is bent 70 over the outer edge of the annulus and retained by the stock part, the said stock part consisting of an internally flanged annulus and a substantially circular shaped piece of fabric, the said piece of fabric being disposed over the outer edge of said second named annulus, and a clamping ring superimposed on the marginal portion of said piece of fabric and disposed in the second named annulus. 80

4. A powder puff comprising interfitting stock and pad portions the latter of which consists of an internally flanged annulus and a substantially circular shaped piece of fabric the marginal portion of which is bent over 85 the outer edge of the annulus and retained by the stock part, the said stock part consisting of an annulus and two pieces of fabric one of which is superimposed upon the other and connected to the central portion of the other 90 piece, the marginal portion of said superimposed piece being bent over the outer edge of the second named annulus and a clamping ring superimposed on the other of said connected pieces and directed into the second 95 named annulus and operating to tension said connected pieces.

5. A powder puff comprising interfitting stock and pad portions the former of which consists of an annulus, and a substantially circular shaped piece of fabric disposed around the edge of the annulus, a second piece of fabric disposed over the inner face of the first named piece, an eyelet or the like connecting the said pieces at their central 105 portions, clamping means disposed in the said annulus and bearing on the marginal portion of the second named piece of fabric and a handle formed of flexible material extending through the eyelet and having its inner end secured to the clamping means.

6. A powder puff comprising interfitting pad and stock portions, the latter of which consists of an annulus, and a substantially circular shaped piece of fabric disposed around the edge of the annulus, a second piece of fabric disposed over the inner face of the first named piece, means connecting the said pieces at their central portions, a clamping ring provided with an upstruck portion, 110 and a handle formed of flexible material extending through the pad portion and secured to the upstruck portion of the clamping ring. 115

7. A powder puff comprising interfitting pad and stock portions, the latter of which 125 consists of an annulus, and a substantially circular shaped piece of fabric disposed around the edge of the annulus, a second piece of fabric disposed over the inner face of the first named piece, an eyelet or the like con- 130

necting the said pieces at their central portions, a clamping ring provided with an upstruck portion and a handle formed of flexible material extending through the eyelet 5 and secured at one end to the upstruck portion of the clamping ring, said pad portion consisting of an annulus, and a substantially

circular piece of soft material extending in and about the annulus, said pad annulus fitting frictionally about the stock annulus. 10

In testimony that I claim the foregoing as my invention, I have signed my name hereunder.

MAX MENKIN.
